TYPE BAR REST

Ralph E. Page, Lagrangeville, and Ronald D. Dodge, Poughkeepsie, N. Y., assignors to International Business Machines Corporation, New York, N. Y., a corporation of New York

Application December 29, 1950, Serial No. 203,348

6 Claims. (Cl. 197—42)

1

This invention relates to typewriting machines.

The principal object of the invention is to provide an improved rebound pad and type bar rest.

An object is to provide a rebound pad and rest which not only reduces rebound to an insignificant amount, but also makes the typewriter considerably quieter in operation.

An object is to provide a type bar rest and rebound pad which is suitable for power operated typewriters.

An object is to provide a rebound pad and rest which floats in the typewriter basket and is weighted to compensate for the different rebound tendencies of the type bars at the end of the basket.

Other objects of the invention will be pointed out in the following description and claims and illustrated in the accompany drawings, which disclose, by way of examples, the principle of the invention and the best mode, which has been contemplated, of applying that principle.

In the drawings:

Fig. 1 is a front view of the type bar rest and rebound pad.

Fig. 2 is a vertical section on the line 2—2 of Fig. 1.

The rebound pad comprises an assembly which is mounted so as to float on two pins 10 which may be secured to and form part of the type basket of a typewriting machine, the invention being particularly suitable for use in power operated typewriters. The framework of the type bar rest consists of a formed strip 11 preferably of stiff sheet steel curved in an arc which is approximately concentric with the printing point on the platen and concentric with the array of type bars in the usual segment (not shown). In the drawings only the two center and end type bars 12 are shown.

The formed strip 11 is shaped with the lugs 11a, 11b which serve to retain in place the rebound pad which, in the present case, is composed of three strips 13a, 13b of a resilient material such as the plastic Vinylite. The two strips 13b are of about the same width as the main part of the metal strip 11 and are snugly retained between the lugs 11a at the sides and the lugs 11b at the ends of the strips 13b. The strip 13a is considerably narrower than the strips 13b and is cemented to the top strip 13b so as to support the type bars 12 adjacent the collide ears 12a. The end lugs 11b are bent over at their ends to overlie the ends of the strip 13a so as to prevent the assembly of strips from springing out of the lugs 55

2

11a. The assembly comprising the strip 11 and the strips 13a, 13b is supported on the pins 10 by means of the spring members 14, each of which is formed with a pair of bent-over lugs 14a loosely pivoting the members 14 on the pins 10, the members 14a being retained on the pins by means of the retaining plates 15 which are sprung into grooves formed in the pins 10 in a well-known way. The members 14 are attached to the strip 11 at points approximately $\frac{1}{4}$ the length of the strip 11 from the ends of the latter, in order to obtain as even a distribution of weight as possible. The assembly supported by the members 14 is also provided with the compensating weights 16 which are secured in any suitable manner to the ends of the strip 11 adjacent the lugs 11b.

It has been found by experiment that it is desirable that the rebound pad and rest have a more or less definite weight distribution related to the positions of the type bars in order to function with maximum efficiency as a rebound suppressing means and it is for this reason that the additional strips 13b are provided, their function being primarily for the purpose of adding weight to the rebound pad although they also assist to a certain extent in cushioning and silencing the rebound. It has also been found that the weights 16 improve the suppression of the rebound of the end type bars which is somewhat different from the rebound of the type bars at the center of the basket arising partly from the fact that the end type bars are somewhat sharply bent adjacent their ends and partly because of the angularity with which the end type bars are disposed in relation to a vertical plane passing through the center of the type basket and the printing point. When the end type bars strike, they move at such an angle that the effect of gravity as a restoring force is considerably less than on the center type bars and their heads must be substantially in a vertical plane passing through the printing point and at right angles to the usual platen whereas the type bars nearer the center are bent only at very small angles.

While there have been shown and described and pointed out the fundamental novel features of the invention, as applied to a preferred embodiment, it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. A type bar rest comprising an arcuate supporting strip, a series of cushioning and weighting strips disposed along the inside curved surface of said strip to form a support for the heads of an arcuate array of type bars, weight members disposed at the ends of said supporting strip so as to increase the weight of said strip at its ends, and resilient means for mounting said supporting strip attached to said supporting strip intermediate the ends and the center of said supporting strip.

2. A type bar rest for a curved array of type bars comprising a curved supporting member, means to yieldingly mount said member to enable translating movement thereof in the directions of the planes of rebound of said type bars, a curved rebound cushion disposed along said member and supporting said array of type bars, and weighting means disposed at the ends of said member to compensate for the different rebound characteristics of the end type bars of said array as compared with the type bars at the center of said array.

3. A type bar rest comprising a curvilinear supporting member having a pad for supporting a curvilinear array of type bars and adapted to add non-rigid weight to said member and also act as a cushion for said type bars and including weight members at the ends of said supporting member,

and a floating mounting for said supporting member.

4. A type bar rest comprising a resilient rebound pad for supporting a curvilinear array of type bars, a curved supporting member for said pad and formed of relatively thin metal, said pad being relatively considerably thicker dimensionally than said member so as to add non-rigid weight to said member, springs for supporting said member, and weights mounted on said member at its ends to increase the weight distribution at the ends.

5. The invention set forth in claim 3 in which the pad comprises a series of separate resilient strips.

6. The invention set forth in claim 1 in which the resilient mounting means comprises a plurality of springs.
